Attorney

UNITED STATES PATENT OFFICE

OLIVER F. PESCH, OF BEVERLY HILLS, CALIFORNIA

SAFETY LOCK

Application filed June 24, 1929. Serial No. 373,403.

This invention appertains to attachments for door locks and has for one of its primary objects the provision of novel means for holding a key in a door lock against unauthorized removal and rotation in an unlocking direction.

Another important object of my invention is the provision of a pivoted locking plate carried by the door adjacent to the keyhole thereof for swinging movement across the keyhole for preventing the withdrawal of the key therefrom, with novel means for locking the plate in a position against accidental displacement from across the keyhole, the plate carrying a stop pin disposed in the path of the key when the plate is in its operative position, thereby preventing turning movement of the key in one direction.

A still further object of my invention is to provide an improved attachment for door locks of the above character, which will be durable and efficient in use, one that will be simple and easy to manufacture, and one which can be placed upon the market at a reasonable cost.

With these and other objects in view, the invention consists in the novel construction, arrangement and formation of parts as will be hereinafter more specifically described, claimed, and illustrated in the accompanying drawings, in which drawings:

Figure 1 is a fragmentary side elevation of a door equipped with the door lock and having my improved attachment incorporated therewith, the door knob and shank for the lock and door being shown in section;

Figure 2 is a vertical section through the door showing my attachment incorporated with the lock and in its operative position;

Figure 3 is a fragmentary rear elevation of the escutcheon or face plate of the door lock showing my improved attachment incorporated therewith;

Figure 4 is a vertical section through the lock and door taken on the line 4—4 of Figure 1 looking in the direction of the arrows;

Figure 5 is a horizontal section through the door showing my improved device incorporated with the lock thereof, and

Figure 6 is a detail perspective view of the improved attachment per se.

Referring to the drawings in detail, where-in similar reference characters designate corresponding parts throughout the several views, the letter A generally indicates a conventional lock for a door B.

The lock A, as shown, is of the mortise type and embodies the inner and outer escutcheon or face plate 5 and 6. These face plates are provided with registering keyholes 7 and 8 which also register with the keyhole in the lock proper.

Associated with the inner escutcheon or face plate 5 is my improved lock attachment C which comprises a flat metal plate 10 having a resilient arm 11 formed on one edge thereof and extending parallel with the lower face of the plate. The outer end of the resilient arm 11 can be bowed outwardly as at 12, for spacing the same from the face of the door, as will be later described. In accordance with my invention the inner escutcheon plate 5 has one edge thereof provided with a slot 13 and the vertical wall of the slot at its lower end is provided with a notch 14 and said vertical edge can be downwardly inclined for leading toward said notch.

The plate 10 is placed on the inside of the escutcheon or inner face plate 5 with the operating arm 11 thereof protruding through the slot 13 and the outer upper corner of the plate 10 is pivoted as at 15 to the escutcheon plate at one side of the keyhole 7 therein. The inner upper corner of the plate has formed thereon or secured thereto the laterally extending stop pin 16 which extends through the keyhole of the lock proper.

In operation of the improved attachment the door is locked from the inside in the usual manner with the bight of the key to the left of the keyhole (referring to Figure 1) after which the arm 11 is swung downward which will raise the plate 10 across the keyhole 7 of the escutcheon or face plate 5, disposing the stop pin 16 in the path of the bight of the key thereby preventing the turning movement of the key in a direction to unlock the door. As the arm 11 is moved downwardly, the same springs into the notch 14 which

locks the plate in position against accidental movement. The pin and the plate effectively prevent withdrawal of the key from the lock and prevent the forcing of the key out of the lock from the outside of the door, or the turning of the key by an unauthorized person.

When it is again desired to unlock the door, it is merely necessary to spring the arm 11 from out of engagement with the upper wall of the notch 14 and swing the arm up which will move the plate 10 below the keyhole 7 and the stop pin 16 from out of the path of the bight of the key. This will allow the turning of the key in the proper direction to permit the retracting of the bolt.

From the foregoing description it can be seen that I have provided an exceptionally simple device which will effectively prevent the turning or the removal of a key in the lock by unauthorized persons from the outside of the door.

Changes in details may be made without departing from the spirit or the scope of this invention.

What I claim as new is:

The combination with a door and a door lock having an escutcheon plate provided with a keyhole registering with the keyhole of the lock proper, of an attachment therefor comprising a guard plate pivoted at its upper outer corner to the inner face of the escutcheon plate, a stop pin carried by the inner upper corner of the guard plate disposed in the keyhole of the lock proper, a laterally extending manipulating arm formed on the lower outer corner of the door plate, and means for locking the arm against movement when the same is in one of its positions.

In testimony whereof I affix my signature.

OLIVER F. PESCH.
